UNITED STATES PATENT OFFICE.

ALBERT J. GURNEY, OF CANTON, OHIO, ASSIGNOR TO THE AMERICAN MINE DOOR CO., OF CANTON, OHIO, A CORPORATION OF OHIO.

SIGNAL-WIRE HANGER.

Application filed November 7, 1923. Serial No. 673,331.

This invention relates to an improved signal wire hanger, being particularly designed for use in connection with my improved signaling system for mines as disclosed in Patent No. 1,523,805, dated January 20, 1925, and seeks to provide a hanger which may be readily attached to the usual trolley wire hanger of a mine for supporting a conductor wire over the trolley wire so that when the trolley wire is pressed upwardly by the trolley of a mine car, incident to the travel of the car along the mine tracks, a circuit will be closed through the conductor wire for energizing certain signals.

15 In the drawings:

Figure 1 is a side elevation showing my improved hanger in connection with a conventional trolley wire hanger.

Figure 2 is a plan view of the assembled hanger, and

Figure 3 is a detail sectional view on the line 3—3 of Figure 1, showing the manner in which the conductor wire hanger is secured in place.

25 Referring now more particularly to the drawings, I have shown my improved conductor wire hanger in connection with a conventional hanger for the trolley wire of a mine. This trolley wire hanger includes the usual insulator 10 from the lower end of which extends a stud 11 and threaded over said stud is a stem 12 upon which are pivoted coacting elongated jaws 13 to engage a trolley wire, as conventionally illustrated at 30 14. Surrounding the stem 12 to coact with the jaws 13 is a wedge member 15 and threaded upon the enlarged upper end of the stem is a nut 16 adjustable for binding the jaws in engagement with the trolley 35 wire.

40 Coming now more particularly to the subject of the present invention, I employ a pair of companion clamping jaws 17 and 18 respectively, bent at their lower margins to define semi-cylindrical gripping portions 19 mating to define a sleeve and extending through the upper margins of the jaws near the ends thereof are clamping bolts 20. As brought out in Figure 2, the jaws are curved longitudinally to extend at one side of the trolley wire hanger while the jaws are of such length that the ends thereof terminate near the plane of the trolley wire, and fitting between the portions 19 of the jaws is 45 a longitudinally curved tubular insulator

21 accommodating a conductor wire 22 therethrough. Thus, as will be seen, the bolts 20 may be adjusted for binding the jaws in engagement with the insulator while the portions 19 of the jaws will provide a protecting sheath for the insulator. Rising from the jaw 18 medially thereof is an angle-shaped arm or bracket 23 the laterally directed free end portion of which is provided with a slot 24 to accommodate the 60 stud 11 of the insulator 10. Accordingly, the free end of the arm may, as shown, in Figure 3, be slipped over said stud between the upper end of the stem 12 and the insulator when the stem may be adjusted upwardly upon the stud for firmly clamping the arm. However, the free ends of the ears defined by the slot 24 are, as best brought out in Figures 1 and 2, bent laterally downward so that said ears will coact 65 with the upper end of the sleeve for locking the arm against displacement. Thus, the hanger will be rigidly and securely mounted upon the trolley wire hanger for supporting the conductor wire 23 above the trolley wire 70 in close proximity thereto.

Having thus described the invention, what is claimed as new is:

1. The combination with a trolley wire hanger, and a trolley wire supported by said hanger, of an auxiliary hanger mounted upon the trolley wire hanger to extend at one side thereof, and a conductor wire supported by said auxiliary hanger above and to one side of the trolley wire in close proximity thereto whereby a trolley wheel may move the trolley wire upwardly and have contacting engagement with both wires.

2. A wire hanger including companion longitudinally curved clamping jaws to accommodate a wire therebetween, and means for adjusting the jaws with respect to each other, one of the jaws being provided with a supporting arm slotted at its free end to accommodate a supporting stud.

3. A wire hanger including companion longitudinally curved clamping jaws bent at their lower margins to define gripping portions to extend about an insulator for a wire, and means extending through the upper margins of the jaws for clamping the gripping portions thereof in engagement with said insulator, one of the jaws being provided with a supporting arm.

4. A signal wire hanger including com-

panion longitudinally curved jaws mating to receive a wire therebetween, and means for adjusting the jaws with respect to each other, one of the jaws being provided with an 5 standing arm having a laterally directed terminal slotted to accommodate the stud of the insulator of a trolley wire hanger.

5. In a device of the class described, the combination with a pair of contractible ears 10 for securing an electrical conductor, suspending means and clamping means for the ears, of means carried by the suspending means for clamping and supporting a second electrical conductor independently of the 15 first-mentioned electrical conductor above and to one side of the first-mentioned conductor in close proximity thereto whereby a trolley wheel may move the first-mentioned conductor upwardly and have contacting 20 engagement with both conductors.

6. In a device of the class described, the combination with a pair of contractible ears for securing an electrical conductor, suspending means and clamping means for the 25 ears, of means carried by the suspending means for fixedly clamping and supporting a second electrical conductor independently of the first-mentioned electrical conductor above and to one side of the first-mentioned 30 conductor in close proximity thereto whereby a trolley wheel may move the first-mentioned conductor upwardly and have contacting engagement with both conductors.

7. A suspending device for a trolley wire 35 and a second cooperating wire comprising means for fixedly clamping the trolley wire, and an auxiliary means carried by the first means for fixedly clamping the second wire independently of the trolley wire above and

to one side of the trolley wire in close proximity thereto whereby a trolley wheel may move the trolley wire upwardly and have contacting engagement with both wires. 40

8. A suspending device for a trolley wire and a second wire comprising means for fixedly clamping the trolley wire, and auxiliary means carried by the said first means for fixedly supporting the second wire independently of the trolley wire near the 45 plane thereof and in parallelism with the trolley wire and spaced above and to one side of the trolley wire in close proximity thereto whereby a trolley wheel may move the trolley wire upwardly and have contacting engagement with both wires. 50

9. The combination with a main hanger, an insulator supporting said hanger, and a wire carried by the hanger, of an auxiliary hanger having coacting jaws, one of which is 55 provided with an arm clamped between the main hanger and said insulator for supporting the auxiliary hanger, and a second wire supported between the jaws of the auxiliary hanger above and to one side of the first mentioned wire whereby a trolley wheel engaging the first wire may move the same upwardly and have contacting engagement with both wires. 60

10. The combination with a main hanger, and a wire supported by the hanger, of an auxiliary hanger carried by the main hanger and provided with longitudinally curved 65 jaws extending at one side of the main hanger in spaced relation thereto, and a second wire supported by said jaws close to said first mentioned wire. 70

In testimony whereof I affix my signature.
ALBERT J. GURNEY. [L.S.]
